DANCING DOLL OR THE LIKE

Silvester Ciccone and Elmer L. King, Jr.,
Norfolk, Va.

Application October 27, 1949, Serial No. 5,732

Term of patent 3½ years

(Cl. D34—4)

To all whom it may concern:

Be it known that we, Silvester Ciccone and Elmer L. King, Jr., citizens of the United States, residing at Norfolk, in the county of Norfolk and State of Virginia, have invented a new, original, and ornamental Design for a Dancing Doll or the Like, of which the following is a specification, reference being had to the accompanying drawings, forming a part thereof, and in which:

Fig. 2 is a rear elevational view.

Fig. 3 is a view of the edge elevation.

We claim:

The ornamental design for a dancing doll or the like, substantially as shown.

SILVESTER CICCONE.
ELMER L. KING, JR.
